UNITED STATES PATENT OFFICE.

CARL WINKLER, OF BERNE, SWITZERLAND.

CASTING MACHINE FOR STEREOTYPE PLATES.

Application filed March 21, 1925. Serial No. 17,320.

To all whom it may concern:

Be it known that I, CARL WINKLER, a citizen of the Swiss Republic, residing at Berne, in the Swiss Republic, have invented new 5 and useful Improvements in Casting Machines for Stereotype Plates, of which the following is a specification.

My invention relates to a casting machine for stereotype plates in which a cock is used 10 for controlling the flow of metal.

It has been found that in such machines the best way of preventing the molten stereotype metal from entering into the bearing is to provide sufficient lubrication. Heretofore 15 this lubrication was carried out in such a way that oil was forced into the bearing during the opening motion of the cock. This was not however sufficient to prevent the stereotype metal from penetrating into the bearing 20 at higher temperatures. According to the invention this drawback is overcome by forcing oil into the bearing both on opening and on closing the cock.

One way of carrying out the invention is 25 shown by way of example in the accompanying drawing.

Fig. 1 is a vertical section through the pump in a plane parallel to the axis of the cock,

Fig. 2 a vertical section through the pump in a direction at right angles to the cock axis, and an end view of the receptacle for the molten metal.

Fig. 3 shows the piping connecting the 35 pump with the two bearings.

The pump has two plungers *a*, *b* which are connected with the opposite ends of a lever *c* fulcrumed at the middle. At their lower ends the plungers are hollow, in order

to take up the suction valves *d*, and they 40 each possess a hole *e* through which the oil in the receiver *f* passes to the suction valves. To the force chamber *g* are connected one or more force pipes *h* which are closed at 45 the top by force valves *i*, in order to prevent the oil from returning to the force chamber during the suction stroke of the plungers. The lever *c* is connected eccentrically with 50 the cock *k* in the bottom of the receptacle *o* by means of the link *l*.

If, now, the cock is turned into the position shown in dotted lines in Fig. 2, the oil 55 collecting in the pressure chamber *g* underneath the piston *b* is pressed through one of the pipes *h* to the bearings *m*, *n*. As soon as the cock is closed again by returning into the position shown in full lines, the piston *b* is raised and the piston *a* lowered, so that oil is pressed by the latter into the bearing 60 *m*, *n*. It will be seen therefore that every movement of the cock *k* is accompanied by mechanical lubrication.

What I claim and desire to secure by Letters Patent of the United States is:

Casting machine for stereotype plates 65 comprising a pot to melt the stereotype metal, a cock to regulate the flow of metal from said pot, and means to lubricate said cock both in opening and closing, substantially as, and for the purpose, set forth.

In testimony whereof I have signed my name to this specification in the presence of 70 two subscribing witnesses.

CARL WINKLER.
